UNITED STATES PATENT OFFICE.

MICHAEL LUERY, OF CHICAGO, ILLINOIS, ASSIGNOR TO MODEL FORM COMPANY, OF CHICAGO, ILLINOIS, A CORPORATION OF ILLINOIS.

ADJUSTABLE MODEL DRESS-FORM.

1,221,550.

Specification of Letters Patent.

Patented Apr. 3, 1917.

Application filed April 16, 1914. Serial No. 832,304.

To all whom it may concern:

Be it known that I, MICHAEL LUERY, a citizen of the United States of America, residing at Chicago, in the county of Cook and State of Illinois, have invented certain new and useful Improvements in Adjustable Model Dress-Forms, of which the following is a specification.

My invention relates to adjustable model forms such as are employed for fitting dresses, an object being to provide an adjustable form having an improved arrangement of parts whereby a more effective adjustment is secured. In connection with dress forms of the adjustable type, it is of course desirable that in changing the adjustment it conform as nearly as possible to natural lines without distortion of the figure. I have found that with my arrangement, improved adjustment of the shoulder and bust are secured.

In the accompanying drawings I have illustrated my invention in which like reference characters indicate like parts and in which—

Figures 1, 2 and 3 are front, side and rear elevations of the preferred form of my invention in its closed position;

Figs. 4, 5 and 6 are front, side and rear elevations of the same form but adjusted to its extreme size;

Fig. 7 is a section through the center of the form looking toward the front thereof;

Fig. 8 is a section through the center of the form looking toward its left arm side;

Fig. 8^a is a section through one of the clamping devices;

Fig. 9 is a perspective view of the form illustrated in the preferred arrangement of cuts;

Figs. 10, 11, 12 illustrate different possible adjustments; and

Figs. 13, 14 and 15 show other methods of dividing the form.

Referring now to the preferred form of my invention as illustrated in Figs. 1 to 12 inclusive, I preferably provide front and rear neck sections 1, 2, 3, 4, front and rear shoulder portions 5, 6, 7, and 8; front and rear intermediate sections 9, 10, 11 and 12; and front and rear waist sections 13, 14, 15 and 16. The neck and intermediate sections are divided by the circular cuts 17, 18 where-

by these intermediate portions may be rotated in a way about the neck portions.

In Figs. 7 and 8 I have illustrated the preferred arrangement for connecting the sections, there being preferably yieldingly adjustable connecting devices for connecting the adjacent sections. Any suitable arrangement for connecting the neck sections at their top may be provided but I preferably employ four inwardly projecting clamping plates as 19, which plates are secured to the neck sections and overlap at a central point so that a supporting rod 20 may project through a slot in said plates, said rod having a threaded end for receiving the clamping handle 21. The rod 20 extends downwardly into a tube 22 supported by a standard 23, there being a thumb nut 24 provided for holding the rod 20 in adjustment. The waist sections of the form have quarter sections as 124 secured thereto and a cross-shaped slotted member 25 is provided having clamping screws 26 extending therethrough into their corresponding sections 124. Member 25 is attached to a collar 27 which is adapted to be fastened to the rod 20 by a set screw 28, when the form is adjusted.

In Fig. 8^a, I have illustrated the preferred form of a clamping arrangement A for the section connecting elements, this clamping arrangement being applied to the different connectors and consisting of a corrugated strip 29 resting against a prong-shaped member 30 and having a clamping element 31 resting against the opposite face of the strip 29. A clamping screw 130 extends through the said elements and has a spring 32 positioned between the clamp plate 31 and the clamping nut 33 whereby said nut 33 may be adjusted to produce different holding effects of the plate 31 upon the connecting strip 29. Except in Fig. 8^a, the strips 29 are not shown corrugated on account of the small scale of the drawings.

A connecting device B is provided for connecting each pair of adjacent front and rear waist sections, there being connecting devices C and D for connecting each waist section at the hip to the adjacent shoulder section. Each pair of front and rear shoulder sections are connected at the side cut by means of connecting devices E and F. Each front waist section is also connected to its

adjacent shoulder section at an intermediate point by a connecting device G. Each pair of adjacent shoulder and intermediate sections is connected at the upper or shoulder portion by a connecting device H, and at an intermediate point by a device J.

The front waist sections 13 and 14 are connected by a connecting device K and the front intermediate sections 9 and 10 are connected by a connector L, the connecting strip 29 of device L having a downwardly projecting strip of a connector M secured thereto, which strip M extends through a clamping device carried by the strip of connector K.

15 The rear waist and intermediate sections are connected by means like K, L and M of the corresponding front parts described.

The front pair of neck sections 1 and 2 are connected at the lower end by a connector N 20 and the upper part of the intermediate sections 9, 10, are connected by a connector O, these connectors N and O being connected by a connector R whose strip 29 depends from the connecting strip 29 of N. Likewise 25 the rear neck and intermediate sections are connected by elements as N, O and R except that the strip 29 of the said rear sections is as shown in Fig. 8.

Each intermediate section is also connected 30 at its inner corner to the corresponding neck section, connectors as S being used at the sections of the front half of the form, and connectors as T at the rear. Connectors S and T have their strips 29 pivotally connected to a plate as 36 which is attached to its corresponding neck section.

Strengthening strips 37 are provided at the neck sections, being preferably riveted so as to maintain the said sections in proper 40 shape.

My form may be adjusted to various shapes, a few being illustrated by Figs. 10, 11, 12. In Figs. 10 and 11 the waist and bust are enlarged without affecting the shoulder, 45 the lower end of the intermediate and shoulder sections 9—10 and 5—6 respectively being drawn outwardly. On account of the curved neck cuts 17—18 and the intermediate sections, the said sections pivot at the neck 50 cuts 17—18 so as to maintain the proper curve from the face of the neck to the face of the bust part of the intermediate sections. Of course the back cuts being similar to the front, like results are secured there. Also 55 I have found that on account of the particular neck cuts and intermediate sections which I employ, a less pronounced angle at the neck cuts 17—18 is secured when the shoulders are raised, as such raise is taken up by 60 both the intermediate and shoulder sections.

In exhibiting dresses it is sometimes desirable to elevate one shoulder only as in Fig. 12, and I have found such adjustment may be easily secured to various degrees. In

such case the front and back intermediate sections are pulled outwardly at the bottom thus swinging on the curved neck cut and the shoulder section may also be drawn outwardly to broaden the shoulders if desired.

In Figs. 4, 5 and 6 the sections are shown 70 adjusted to their fullest extent and it will readily be seen that many different shapes and sizes may be secured by adjusting the sections to intermediate positions.

In order to permit a more free and easy 75 adjustment of the sections, pivoted joints are provided at suitable connections where one connecting strip 29 is riveted to another, or to a metal part as at S and T, and also the screws 30 may pivot slightly in the form 80 section.

In Figs. 13, 14 and 15, I have illustrated other methods of cutting the form in connection with curved neck cuts. In these figures the connecting devices are shown by 85 dotted lines, these indicating the preferred positions thereof whereby effective adjustment is secured.

In the preferred form of my invention I provide intermediate and shoulder sections 90 as in Fig. 9 but certain of the advantages of the curved neck cuts are also obtained with a form sectioned as in Fig. 13. Therefore it is to be understood that I do not desire to limit my claims to the improved features of the neck cuts and means for joining the resulting sections to the form of Fig. 9, but aim to cover all such changes and modifications as come within their spirit and scope.

Having described my invention, what I claim as new and desire to secure by United States Letters Patent is:

1. A dress form divided vertically through its neck from shoulder to shoulder and front to back so as to constitute four vertical divisions, vertical cuts through the shoulder to provide front and rear shoulder and intermediate sections, curved cuts at the base of the neck providing independent front and rear neck sections at each side, and connecting devices for said sections to permit independent adjustment thereof.

2. A dress form divided vertically through its neck and shoulders and front to back so as to constitute four vertical divisions, a horizontal cut through the form between the bust and waist, front and rear curved cuts dividing the neck and bust, vertical cuts through the shoulders so as to provide front and rear shoulder and intermediate sections, and connecting devices yieldingly connecting adjacent sections to permit independent adjustment thereof.

3. A dress form divided vertically through its neck from shoulder to shoulder and centrally from front to back, so as to comprise four neck sections, front and rear curved

cuts at the base of the neck for dividing the neck sections from the adjoining bust, shoulder and back portions so as to provide front and rear shoulder and bust sections, horizontal cuts extending around the form between the shoulder and waist, and connecting devices for said neck and shoulder sections whereby said shoulder and bust sections may be adjusted independent of the 10 neck sections.

4. A dress form divided vertically through its neck from shoulder to shoulder and centrally from front to back so as to comprise four vertical divisions, front and rear curved

cuts at the base of the neck providing front 15 and rear combined shoulder and bust sections at each side, horizontal cuts extending around the form between the shoulder and waist, and connecting devices whereby any of the neck or body sections may be independently adjusted and held. 20

Signed by me at Chicago, in the county of Cook and State of Illinois, in the presence of two witnesses.

MICHAEL LUERY.
